APPARATUS FOR TREATING METAL SHEETS

Evelyn Edwin Griffiths, Blundellsands, England

Application November 30, 1931, Serial No. 578,103,
and in Great Britain December 3, 1930

20 Claims. (Cl. 263—8)

This invention relates to apparatus for treating metal sheets, such for example as furnaces for annealing metal sheets. The type of such apparatus to which the invention is applicable is that in which the upper portion of the furnace is traversed by an endless conveyor to which the sheets to be treated are attached by their upper edges, so that they are maintained in a vertical dependent position by their weight, and are passed through the furnace in succession in a common vertical plane, entering and leaving the furnace by closure means which thus require to be opened by the minimum amount only to admit the sheet; and the object of the invention is to provide improved means by which the sheets are fed to the conveyor and discharged therefrom, and improved closure means.

The invention is specially applicable to sheets having their edges beaded to form attachment means, but it is applicable also to plain sheets, and includes arrangements by which the sheets may be fed directly to the main conveyor traversing the furnace, or to a transfer conveyor between the feeding table and the main conveyor, or, in the case of beaded sheets, to a bar or the like equivalent of the transfer conveyor.

I have in the accompanying drawings illustrated my invention as applied to an apparatus for annealing sheets by a continuous process.

30 In the drawings:—

Figs. 1 to 6 illustrate a general arrangement embodying one modification in which transfer belts are employed to feed beaded sheets to the main furnace conveyor.

35 Figs. 1, 2 and 3 together, constitute an elevation of the apparatus.

Fig. 1 relates to the left-hand part of the apparatus up to the line x , x .

Fig. 2 is the central part of the apparatus between the lines x , x and y , y .

40 Fig. 3 is the right-hand part of the apparatus from the line y , y .

Figs. 4, 5 and 6 together constitute a corresponding plan view, the lines x , x and y , y , being similarly indicated.

45 Fig. 7 is a fragmentary elevation of a modification of the feeding table, and

Fig. 7A is a corresponding plan.

50 Figs. 8, 9, 9A and 10 illustrate the details of construction of the preferred form of main conveyor sheet attachment means for sheets having turned-over or beaded upper edges.

Fig. 8 being an elevation in transverse section, 55 on the line VIII, VIII, of Fig. 10.

Fig. 9 a side elevation of a conveyor link with a pair of carrier bars,

Fig. 9A a fragmentary side elevation partly in conventional section, of the attachment means, and

60

Fig. 10 a plan view of Fig. 8.

Figs. 11, 12 and 13, which are fragmentary end elevations, illustrate three modifications of attachment means for the main conveyor adapted to take sheets having plain upper edges, said attachment means being carried by the carrier bars.

Figs. 14, 14A and 15, and 15A illustrate the means employed to prevent leakage of hot gases at the openings into and out of the conveyor 70 chamber through which the conveyor and carrier bars pass,

Figs. 14 and 14A being end elevations in transverse section, and

Figs. 15 and 15A being sectional side elevations.

Figs. 16 and 17 are fragmentary plan views of pneumatic devices for preventing leakage at the entrances and exits of the furnace and cooling chamber through which the sheets pass.

80

Figs. 18 to 23 are views to a larger scale and show the arrangement of the transfer belt and portions of the main conveyor,

Fig. 18 being an elevation,

Fig. 19 a plan, and

85

Figs. 20 to 23 conventional transverse sections,

Fig. 20 showing the plate sheet K while it is still supported by the table D, 21 being in section on the line XXI, XXI, and

Figs. 22 and 23, respectively, being in section 90 on the lines XXII, XXII and XXIII, XXIII of Fig. 18.

Figs. 24 and 25 illustrate, more or less diagrammatically a modification in which the axis of the sprocket wheels of the transfer conveyor 95 and main conveyor are respectively vertical and horizontal,

Fig. 24 being an elevation, and

Fig. 25 a plan.

Figs. 26 and 27 are views similar to 24 and 25 100 and illustrate the arrangement in which the axes of the sprocket wheels of the main and transfer conveyors are respectively, vertically and obliquely disposed,

Fig. 26 being an elevation, and

105

Fig. 27 a plan.

Figs. 28 to 31 illustrate diagrammatically the arrangement in which the sheets with beaded edges are transferred by means of a fixed bar instead of a transfer conveyor.

110

- Fig. 28 is an elevation.
- Figs. 29 and 30 are conventional sections on the lines XXIX, XXIX and XXX, XXX of Fig. 28.
- Fig. 31 is a conventional section on the line 5 XXXI, of Fig. 28.
- Figs. 32 and 33 are, respectively, an elevation and a plan and illustrate a modification in which the sheets are fed directly into pivoted clips on the main conveyor.
- 10 Figs. 34 and 34A are respectively a plan and a side elevation of the preferred form of hook for "floating" clips of Figs. 9 and 9A.
- Figs. 35 to 38 show the arrangement for feeding and attaching to the conveyors sheets having 15 plain upper edges suitable for the arrangement illustrated in Figs. 24 and 25.
- Fig. 35 being a transverse sectional elevation to a small scale, and
- Figs. 36, 37 and 38 being fragmentary transverse sectional elevations to a larger scale, which may be regarded as being taken at the respective points XXXVI, XXXVII, XXXVIII of Fig. 25.
- Figs. 39 to 43 illustrate the arrangement for feeding and attaching to the conveyors sheets having plain upper edges suitable for the arrangement illustrated in Fig. 26 and 27,
- Fig. 39 being a transverse section to a small scale, and
- 25 Figs. 40, 41, 42 and 43 being transverse sections to a larger scale, which may be regarded as being taken at the respective points XL, XLI, XLII, XLIII of Fig. 26.
- Figs. 44 to 46 illustrate pivoted grippers for the main conveyor for sheets having plain edges 35 which are transferred directly from the feeding device to the main conveyor and suitable for the arrangement illustrated in Figs. 32 and 33.
- Figs. 44, 45 and 46 are transverse sections 40 which may be regarded as being taken respectively at the points XLIV, XLV, XLVI of Figs. 33.
- Referring first to Figs. 1 to 6:—
- A is the furnace; a_1 the entrance through which the sheets pass into the furnace, (see Fig. 4).
- 45 O is the cooling chamber; O1 the portal chamber, and a_2 (see Fig. 5) the exit from the furnace; and o_1 and o_2 , respectively, the entrance to and exit from the portal chamber, (see Figs. 5 and 6).
- 50 The preferred construction of furnace and the cooling chamber would be that described in the specification to patent applications Serial Nos. 376,940 and 451,748.
- 55 C is the main conveyor shown conventionally for clearness in Figs. 1 to 6 in chain-dotted lines.
- In this modification the conveyor C is carried by two sprocket wheels c_1 , c_2 , the axes of which are vertical.
- 60 D is the feeding machine table; E is the sheet beading machine; T the transfer belt by which the sheets are transferred from the feeding table to the main furnace conveyor C; the transfer belt T is carried by two sprocket wheels t_1 and t_2 which in this modification have their axes horizontal; J (see Fig. 3) is the sheet discharging end of the apparatus.
- The parts on the entrance side of the furnace including the main sprocket wheel c_1 are 70 carried by a suitable framed structure H; the main sprocket c_2 is carried by the framed tower H2.
- The several parts may be driven in any convenient manner. In the example illustrated a 75 horizontal driving shaft S is provided, by which
- the right-hand or forward sprocket wheels of the main and transfer belts are driven; the main sprocket wheel c_2 is driven by the gearing 1, vertical shaft 2 and gearing 3; the rear main sprocket wheel c_1 is carried in bearings which are spring 80 or gravity controlled (for example by a weight V) to take up the slack, and is driven by the main conveyor itself so that the front or working side of the latter is maintained taut; the forward sprocket wheel t_2 of the transfer conveyor is driven from the rear sprocket wheel c_1 of the main conveyor by the gearing 4, 5, 6 and 7 (Figs. 1, 4 and 18) in which a spur wheel 7, on the shaft of the sprocket wheel c_1 gears with a pinion 6 connected by the shaft 10 bevel wheels 11, shaft 90 13, sprocket wheel 5 and chain 12 to the sprocket wheel 4 on the driving shaft of the sprocket t_2 of the transfer conveyor. The longitudinal movement, relatively to the driven pinion 6, with a fixed axis, of the gear wheel 7 keyed on the axis 95 of the movable sprocket wheel c_1 imparts secondary angular movement to the said pinion in such manner that intermeshing alignment between the sheet attachment means of the transfer conveyor and the main conveyor, respectively, is maintained, with the result that the vertically disposed sheets are transferred, without any tendency to dislocation or distortion, from the transfer conveyor to the main conveyor.
- The beading machine E is driven by the gear- 100 ing 8, from the motor e_1 .
- In the modification Figs. 1 to 6 the sheets are supported by their turned-over edges from the attachment means, (including cam-operated grippers) provided on carriers attached to the 110 links of a main conveyor chain C which passes through a conveyor chamber W (see Fig. 8) in the furnace so that the conveyor is protected from the furnace gases, the carrier bars B (see Fig. 8) extending through a narrow longitudinal slot w' 115 between the conveyor chamber W and the furnace.
- In other modifications, to be described later, the sheets may have plain upper edges which are adapted to be gripped by frictional gripping devices attached to the said carried bars. The attachment means in each case are preferably constructed so that they form "floating" attachments 120 capable of limited horizontal and vertical movement relatively to the conveyors, so that the attachment means are adapted to accommodate 125 themselves to any want of alignment or inequalities of the track, conveyor or sheets.
- Referring to the construction of the main conveyor C, see Figs. 8 to 10, the main conveyor is an 130 endless chain mounted on sprocket wheels c_1 , c_2 respectively located at opposite ends of the apparatus; the forward moving side of the chain passes through the chamber W located above the furnace and communicating with the furnace 135 through a narrow longitudinal slot w_1 .
- The lower part c_{11} of each link of the conveyor C has attached to it or formed integral with it brackets c_{12} to which are bolted a frame c_{13} , and bearing blocks c_{14} , the latter being adapted to 140 slide on longitudinal tubular guides c_{15} , which are made hollow so that cooling water may be circulated therethrough; the guides are fixed to a bed-plate c_{16} by the angle brackets c_{17} , and the tail end $c_{13'}$ of the frame c_{13} runs in a guide c_{18} , 145 carried from the bed-plate c_{16} ; the bed-plate is secured to a length of rolled steel joist c_{19} carried in the brick work of the furnace A.
- The frame c_{13} forms a cantilever and is provided with end lugs c_{20} , and intermediate lugs c_{21} , 150

to take a pivot pin c_{22} on which are pivoted two carrier bars B , each having a pair of lugs b_1 through which the pivot pin c_{22} passes, so that the respective carrier bars can angle to a limited extent about the pins c_{22} . This amount of angling may be limited in any convenient manner, for example the upper edge b_3 of each carrier bar is located between the two jaws c_{21}' cast integral with the lugs c_{21} , these jaws limiting the angular movement of B about the pin c_{22} .

The lower end of each carrier bar is provided with a slot hole b_4 , with nibs b_5 and facings b_6 to take the parts next to be described.

The turned-over top k_1 of each sheet K is supported by a suitable number of hook parts F (see Fig. 9A) each pivotally attached to a carrier bar B by a bolt f_1 passing through the hole f_2 in the hook part F . The lower end of F is hooked shaped as at f_3 , and the upper end has a palm f_4 (see Figs. 34 and 34A) which plays between the nibs b_5 of the carrier bar so as to prevent or limit the angular movement, in a longitudinal plane, of the hook part F about the carrier bar B ; the upper end of F is also provided with a lug f_5 which is employed, at certain portions of the travel of the conveyor, to limit, as hereinafter described, the extent of vertical movement of the parts carried by the bolt f_1 .

The sheets are held in place on the hooks by the pivoted grippers G having holes g_1 which fit the bolts f_1 , the hole g_1 being eccentric to the curvilinear gripping surface g_2 which engages with the top side of the turned-over edge k_1 of the sheet K ; each gripper G is provided with a wing part g_3 which engages the outer surface of the sheet and prevents the sheet from slipping off the hook by outward lateral movement. The shape of the curvilinear part g_2 (usually a circular arc struck from a point eccentric to the pin f_1) is such that any tendency for a sheet to lag behind the hook and gripper is prevented by the wedge-like grip of the part g_2 , which increases with any tendency of the sheet to lag.

Each gripper is provided with an ear g_5 , adapted to engage with a longitudinal fixed cam bar c_3 which when the ear g_5 engages the inclined part of the cam bar, releases the gripper by turning it about its pivot f_1 ; this takes place when the hook is located at that part of its travel at which the sheets are fed to, or removed from the conveyor, such pivotal movement drawing the part g_2 away from the hook.

The sheets with the turned-over edges k_1 are fed as hereinafter described directly onto the hooks f_3 of the part of the main conveyor which is entering the furnace, or on to a transfer conveyor T (see Fig. 1) which transfers them on to the said hooks in the manner hereinafter described.

The said hooks, when the sheets are hooked on them, are held in their lowermost position by the engagement of a longitudinal cam bar c_4 (shown in chain dotted lines Fig. 9A), with the lug portion f_5 of the hooks F ; and the gripper G is held in the position shown in chain dotted lines at the left-hand side of Fig. 9 so that its engaging surface g_2 and wing part g_3 are clear of the sheet K , this movement of the gripper being effected by the engagement between a lug g_5 on the gripper and the underside of the longitudinal cam bar c_3 (shown in chain dotted lines in Fig. 9A).

The underside of the cam bars c_3 , c_4 are so shaped that before the carrier bars B enter the furnace the lugs b_5 and g_5 are left free to per-

mit vertical movement of the hook, and pivotal movement of the gripper, and at a point further forward the lugs g_5 of the gripper engage with the short longitudinal cam c_6 (see also Fig. 19) which turns the gripper into the position in which it retains the sheet K in position on the hooks; this position is shown in full lines in Fig. 9 and in Fig. 9A.

A longitudinal guide bar c_5 , see also Figs. 9A and 19, is usually fitted at the lead-in part of the conveyor, which, as the sheets enter the furnace, serves to keep the sheets in position on the hooks, until the cam bar c_6 turns the gripper into the position shown in Fig. 9A. The position of the cam bars c_3 and c_4 and c_6 and guide bar c_5 are shown in plan view in Fig. 19.

The construction of attachment means described is suitable for sheets with turned-over edges, and is the arrangement adopted in the case of comparatively thin sheets.

In some cases, with comparatively thick sheets, for example, it is desirable to provide means for attaching the sheets to the conveyors which render it unnecessary to turn over the edge of the sheet to take hooks as above described; in such cases the grippers, instead of merely holding the sheets in place as described, form one of the attachment elements for the sheets on the carrier bar B .

Figs. 11, 12 and 13 show suitable arrangements for this purpose.

In Fig. 11 the hook part F of the modification described is replaced by a clamp F_2 slotted at f_6 to take the bolt f_1 carried by the lower part of the carrier bar B ; the lower end of F_2 is serrated as at f_7 ; and to a lug f_8 formed on F_2 is fitted a bolt f_{11} on which is pivoted the gripper part G_2 having a serrated portion g_6 which aligns with the serrations f_7 ; the part G_2 is weighted so that the overhung end is drawn downwardly by gravity so that the upper edge of the sheet K , inserted between the serrations f_7 and serrations g_6 , is firmly gripped and supported as the sheets are carried through the furnace. The pin and slot connections (f_1 and f_6) permit limited angular and vertical movement, in addition to the angular movement permitted to the carrier bar B , as above described.

When the sheets K are fed to the gripping devices, as hereinafter described, the gripper G_2 is opened by the engagement of a longitudinal cam bar g_8 (shown in dotted lines), with the tail piece g_7 of the gripper G_2 ; longitudinal cam bars f_9 , also shown in dotted lines, are fitted to engage with wings f_{10} on F_2 so as to hold F_2 fixed in its lowermost position relatively to the carrier bar, and to prevent angular movement thereof, when sheets are fed to or removed from the conveyor.

Fig. 12 shows a modification of the arrangement last described, the bolt f_{11} on which the gripper G_3 is pivoted is on the same side of the clamp F_3 as the gripper, and the serrated portion g_9 is struck from a radius the centre of which is eccentric in respect to the centre of the bolt f_{11} , and the gripper G_3 is weighted so that it normally tends to turn in the direction of the arrow. The sheet K is gripped between the serrated surface f_{12} of the clamp and the serrated surface g_9 of the gripper and the gripping action is augmented should the sheet tend to slide downwardly; when it is desired to open the gripper, a longitudinal cam bar g_{11} engages the arm g_7 of the gripper G_3 ; the clamp has wings f_{10} , and longitudinal cam bars f_9 are fitted as before to

engage the wings, and hold the clamp against vertical movement when the sheets are fed to or discharged from the conveyor.

The arrangement shown in Fig. 13 is substantially similar to that last described, and is similarly lettered and differs only in respect to the provision of a plate g_{12} pivotally carried on a pin f_{13} secured to the clamp F_4 ; when the sheet K is inserted it fits between the pivoted plate g_{12} and the serrated portion f_{12} , and the grip is obtained by the eccentric portion g_{13} of the gripper G_4 pressing on the plate g_{12} .

The object of this arrangement is to prevent any upward movement of the sheet K , due to inequalities of the track or other cause, from rotating the gripper G_4 and so loosening the grip.

The gripper parts G_2 , G_3 , and G_4 in the respective arrangements of Figs. 11, 12 and 13 laterally over-hang the pivoted part so that the serrated parts g_6 or g_9 or the plain part g_{13} as the case may be align with the serrated parts f_7 or f_{12} , in which case the parts which carry the bolts f_{11} are laterally located. The tail pieces g_7 may be centrally arranged and pass through a slot f_{14} as in Fig. 13, and pass through a slot in the plate g_{12} as shown in Fig. 13.

This pivotal attachment to the conveyor of the depending carrier bars of the main conveyor which permits limited lateral movement, and the slotted connection of the stud carrying the hooked portion and its gripper, or carrying the clamp and its gripper, which permits vertical movement, thus provides automatic means which give freedom of movement in two planes and so prevents distortion of the sheets due to accidental want of alignment of any of the parts.

From the nature of the several modifications described by way of example, it will be seen that the details of construction of the "floating" supporting devices and of the grippers for use with the hook and turned over sheet, or for gripping the plain top of the sheet, may be varied in accordance with the type of furnace to which the invention is applied; for instance, the said arm may be of a material sufficiently thin to have lateral flexibility, and it may be found unnecessary to restrict the amount of lateral movement of the vertical arm; G_1 , G_2 , G_3 , G_4 may be replaced by toggles so arranged as to give a nipping or gripping action equivalent to that described.

At each end of the furnace, sleeves or frames M (Figs. 14 and 15) are provided, through which the conveyor passes into and out of the conveyor chamber of the furnace A , and into and out of the cooling chamber O , and its portal chamber O_1 ; the interior transverse contour m_1 of the frames follows closely the outside cross sectional contour of the conveyor (see chain dotted line Fig. 8) so as to leave a minimum working clearance; each of the frames M is of sufficient longitudinal length to ensure that an efficient seal is formed by reason of the fact that escaping gas has to pass between the small clearance spaces between the walls of the frames and the several elements of the conveyor which are within the frames at the same time; owing to their length, these frames also form effective guides for the conveyor, which are operative to prevent fouling should one of the sheets tend to jam.

The openings at the ends of the furnace A and cooling chamber O , formed by the frames M through which the conveyor chain and carrier bars enter and leave the said furnace and chamber, are further made effective to prevent leakage of furnace or cooling chamber gases, by being

pneumatically sealed, by carrying a pipe R , (see Figs. 14A and 15A) transversely round the profile of the opening; the curved portion of the said pipe being provided with holes or nozzles r_1 through which air or other gas is forced so as to produce an equilibrium of pressure thus tending to prevent the passage through the said openings of cold air into or hot gases out of the furnace.

In order to prevent the conveyor chamber W and the working parts therein from becoming unduly heated by access of furnace gases to this chamber, even where a sealing pipe R is fitted as described, we arrange to supply the conveyor chamber at one or both ends or at any suitable intermediate point, with air or other gas, the pressure and/or temperature of which are so regulated as to preserve the necessary balance to prevent access to this chamber of the hot gases from the furnace.

Owing to the difference of temperature at different heights, and therefore to the difference of pressure at different heights in the furnace, of the gases within the furnace, and within the cooling chambers respectively, there is a tendency owing to the want of balance of pressure for a flow of gases from the furnace to the cooling chamber or vice versa. In order to overcome this objection we provide, as shown at Fig. 2, near the top of the cooling chamber O , balancing pipes S' , through which air or inert gas at suitable temperature and pressure is supplied to the cooling chamber so as to cause the flow of gas therein to be from the top to the bottom, and thus maintain in the upper parts a pressure which would balance the gas pressure in the upper part of the furnace, and so further serve to prevent the flow of gas through the connections such as the sleeves M , between the furnace A and the cooling chamber O .

Should the amount of inert gas added to the cooling chamber not be sufficient to maintain the necessary drop in pressure from the top to the bottom of the cooling chamber, such drop may be produced by withdrawing some of the said gas from the bottom of the chamber and re-introducing it at the top, in addition to the fresh gas which is being constantly added through the pipes S' .

A very effective sealing of the conveyor chamber from the furnace can be obtained by blowing the inert gas into the chamber at a high velocity and pressure by means of a pipe running the full length of the slot, the pipe c_{15} (see Fig. 8) could be employed for this purpose, or another pipe U running along the opposite side of the roof slot w_1 also shown in Fig. 8, might be employed, as this would enable the water cooling of the track and conveyor chamber to be maintained.

The furnaces are built so as to deal with comparatively large thin sheets, which are usually supplied to the machines in piles of sheets horizontally superposed; such sheets are much too thin to enable the attendant to lift the top sheet and turn it by hand into proper vertical alignment to enable it to be attached to the grippers of the main conveyor; and according to the present invention the top sheet of the pile is transferred, whilst approximately horizontal, by the attendant (an operation comparatively easily performed) to a table which is horizontal or inclined to the horizontal at a comparatively acute angle; the sheet is moved along the table until the edge which is to be the top

edge, by which it is to be attached to the conveyor, is in alignment with the attachment means on the transfer conveyor, or on the main conveyor, in the manner hereinafter described. 5 Where the top edge is to be beaded to form a hooked attachment, a beading machine to bead the top edge may be fixed to the said table, so that the said edge is beaded before the sheet is fed forward to the conveyor, the said beaded edge being caused to engage either with the hooks on the main conveyor or on a transfer conveyor, or with a bar which may take the place of a transfer conveyor; the sheet in each case as it passes from the table being allowed 10 to turn under the action of gravity from the horizontal into the vertical, in which latter position, with its top edge secured to the main conveyor it is passed through the furnace and cooling chamber.

20 Referring particularly to Figs. 1 and 4.—D are the supporting means on to which the sheets to be treated are placed in succession in order to be squared and aligned; said means usually take the form of a slotted table, the top of which is in alignment with the sheet attachment means on the forwardly moving part of the transfer conveyor T.

25 P^1 are squaring fingers slidable in grooves p^1 in the table; each finger is attached to a link 30 of the corresponding chain p^2 ; the three chains p^2 are carried by pairs of sprocket wheels p^3 and p^4 , the sprocket wheels p^4 being keyed to a common shaft p^5 so that movement, say from left to right, imparted to any one of the fingers 35 causes all of the fingers to move in alignment across the table.

30 The sheets K taken from say a pile k^2 of horizontally disposed sheets supported on a stand k^3 are laid in succession on the table D (as shown in chain dotted lines Fig. 4) so that their rear transverse edge k^4 abuts against the three squaring pins P^1 when the latter are in the extreme left-hand position; the sheet is then slid 40 transversely across the table until its edge k^1 , by which it is attached to the conveyor, abuts against the aligning stop d^2 ; the sheet is thus squared and aligned, and its edge k^1 is in operative relationship to a reciprocating beading machine E which is of any suitable construction, and is caused in well known manner to 50 make its beading stroke by the depression of a pedal e^2 , which operates the driving clutch, which connects the beading die to a part of the machine continuously driven by the electric motor e^1 . The beading machine makes its stroke and beads over the edge k^1 of the sheet, as shown, for example, in Fig. 23. The beading so formed is in longitudinal alignment with the attachment means of the transfer conveyor 60 T mounted on sprocket wheels t^1 and t^2 (see Fig. 4).

65 The construction of the transfer conveyor will be understood by reference to Figs. 18, 20 and 21;—the links T of the transfer conveyor are provided with rollers 36 which are guided in channels t^9 supported from the main frame-work of the machine, and each link carries a plate t^3 to which are attached hook members t^4 , which hook members as they travel round 70 with the transfer belt have their locus in a vertical plane in alignment with the beading machine E; if, therefore, a sheet K which has been squared and aligned as described, be pushed forward by the operation of the attendant in 75 moving the squaring fingers P^1 forwardly, the

said sheet will be brought into connecting relationship with the hooks t^4 , as shown in Fig. 20, the beaded edge k^1 of the sheet overhanging the edge of the table D. The sheet passes under rollers 37 carried from a frame bar 35, which rollers hold the edge k^1 of the sheet in contact with the hooks t^4 . From the frame bar 35 are carried a series of pivoted latches t^5 , the depending ends of which are turned up by the leading edge of the sheet K, whilst the plane of the sheet remains horizontal. 80

85 When substantially the full length of the edge k^1 of the sheet is located over the corresponding group of hooks t^4 , the sheet passes off the table D, its free outer end being supported by a bar d^3 (see Fig. 4); when the sheet is clear of the table the central portions droop downwardly and the free end is gradually drawn transversely over the bar d^3 , the sheet falling into the vertical position shown in Fig. 21, the sheet being then supported by the engagement of its beaded edge k^1 with the hooks t^4 and being carried forwardly by the hooks t^4 .

90 The links of the main conveyor are, as described, provided with pivoted carrier bars B, and these in turn carry the hooks F, and the grippers G; the hooked portions f^3 of the former having their locus in the same vertical plane as the locus of the hooks f^4 . 95

100 The forward end of the transfer conveyor T droops as it passes over the sprocket wheel t^2 , so that as the sheets are transferred from the hooks t^4 of the transfer conveyor to the hooks F of the main conveyor, the former hooks move vertically downwardly clear of the beaded portions k^1 , and leave the latter supported by the hooked portions f^3 of the main conveyor (see Figs. 22 and 23).

110 As the beaded edge of the sheet comes on to the hooked parts f^3 of the hooks the latter are held in their lowermost position (see Figs. 9A, 18 and 19) by the cam c^4 which engages the lugs f^5 of the hooks; at the same time the grippers G, by engagement of the cam c^3 with the lugs g^5 , are lifted clear of the beaded portion k^1 ; and 120 during this part of its travel the sheet is held in engaging position laterally by the guides c^5 .

125 When the lugs g^5 engage with the cam g^6 (see Fig. 18) they turn into the position shown in Fig. 23 and in full lines in Fig. 9, where they hold the beaded part k^1 firmly in position on the hooked parts f^3 ; the wing portion g^3 of the gripper serves to hold the sheets laterally in position after they have passed the guides c^5 ; the sheets are thus attached to the main conveyor 130 and, attached to and pendant from the main conveyor, they pass through the furnace where they are subjected to the necessary temperature for annealing or other purposes, and are then carried into the cooling chamber O, where they are 135 cooled; and they pass out of the cooling chamber at the end J of the apparatus with the conveyor and are unloaded in any convenient manner.

140 The cooling chamber O is fitted with a portal chamber O^1 (see Fig. 2) to which air at a pressure higher than the atmosphere is admitted by a pipe similar to the pipes S'.

145 The vertical opening a^1 , which forms the entrance to the furnace through which the sheets pass into the furnace and the exits by which the sheets leave the cooling chamber, are made as narrow as possible; the width of such openings must, of course, be great enough to permit entry of the sheets, the surfaces of which may be deformed so that they do not lie in a vertical plane; 150

and in order to prevent leakage into or out of the furnace and cooling chamber, these openings are sealed by air jets obliquely directed on to opposite sides of the sheets. Vertical pipes Y supplied with air under pressure, are located on opposite sides of the openings a1 as shown in Figs. 16 and 17, and these pipes are perforated at intervals so as to provide nozzles for the issuing jets of air; at the lower parts of the openings a1, the nozzles are directed outwardly as shown in Fig. 16, so as to prevent leakage of air into the furnace where the pressure within the lower portion of the furnace is usually below that of the atmosphere; the nozzles at the upper ends of the openings a1 may be directed normally or inwardly, so as to prevent the leakage out of hot gases from the upper parts of the furnace where the pressure is usually slightly above that of the atmosphere. Similar pipes Y are located on opposite sides of the outlet O2 as shown in Fig. 6.

Figs. 7 and 7A show a modification of the feeding table and squaring fingers; in this modification the stack of sheets K is placed in front of the operator who stands in a recess d10 formed in the table D and pulls the top sheet K down the skids d11 on to the table D; the squaring fingers P¹⁰ are formed at the end of levers p12 keyed to a shaft p11 so that angular movement is imparted to them instead of sliding movement as in Fig. 1; d2 is the transverse aligning pin; T⁶ is the transfer conveyor carried on sprocket wheels t20 and t21; c40 is the rear sprocket wheel of the main conveyor and B are the carriers of the main conveyor C constructed as described in connection with Figs. 8 to 10; the aligning and the feeding of the sheets is as described in connection with Figs. 1 to 6.

In Figs. 24, 25, 26 and 27 the table D, squaring fingers P¹, and aligning pin d2 are as described in reference to Figs. 1 and 4; but in these figures additional means are shown to control the sheets after they leave the table D and before they turn into the vertical; such means comprise two pairs of feed belts d20 and d21 carried on pulleys d22 mounted on shafts d23 driven in any suitable manner so that the contacting portions of the belt have the same lineal speed as the transfer belt.

In Figs. 32 and 33 belts d30 and d31, similar in function to the belts d20 and d21, are carried on pulleys d32, mounted on shafts d33; the adjacent parts of the belts are held in contact by skids d34 and d35; d35 being fixed and being under the upper run of the belt d31, and d34 having a toggle attachment d36 and weight d37 by which downward pressure is exerted on the skid d34, forcing the adjacent parts of the belt together, and thus ensuring adequate grip between the belts and the interposed sheets; d38 are jockey pulleys to maintain the tension of the belt.

Referring to the modification illustrated in Figs. 24, 25 and 35 to 38:— the feeding machine is constructed substantially as described in connection with Figs. 1 to 6 except that in this case the beading machine is dispensed with, the axes of the sprocket wheels t11 and t12 (see Figs. 24, 25 and 35) of the transfer conveyor T² are vertical, and the axes of the sprocket wheels c7 of the main conveyor C² are horizontal; the general arrangement is shown in Figs. 24, 25 and 35 the latter being an end elevation to a larger scale than Figs. 24 and 25; the details of the gripping devices for the transfer conveyor are shown in Figs. 36 to 38; the gripping devices for

the main conveyor being shown in Fig. 12.

As stated, the sheets K require attachment to the gripping devices of the transfer conveyor whilst they are in the horizontal position shown in Figs. 24 and 25; the gripping devices suitable for this purpose are illustrated in Figs. 35 to 38.

The transfer conveyor T² is guided in a suitable rectangular guide 38 (see Fig. 35) by means of the rollers 39 journaled on the link pivots of the conveyor, which links are maintained vertical by the guides 38, and maintained at the right height by the slides 40; the grippers comprise a jaw-like member t10 pivoted by the pin 41 to a lever 42 which in turn is pivoted by the pin 43 to the links of the conveyor or brackets carried by the links; a gripper g10 is pivoted by the pin 44 to the member t10, and a spring 45 is connected between an arm on the member t10 and an arm on the gripper g10, and tends to turn the gripper so that its serrated edge 46 (which is eccentric to the pivot pin 44) is brought nearly into contact with the edge 47 so that a sheet introduced between 46 and 47 is frictionally gripped between these surfaces in such manner that any tendency to withdraw it when gripped increases the grip. The gripper g10 is fitted with an arm g10' adapted to be operated by a longitudinally disposed cam bar 48 and a similar cam bar 49 is provided and adapted to operate the arm 42, a further cam bar 51 may be fitted to control the movement of the part t10.

As the transfer conveyor passes along parallel with the left-hand edge of the table of the feeding machine D the attachment gear described is, by the action of the cam bar mentioned, turned into the position shown in Fig. 36, the gripper G being opened so that the sheet K as it is fed by the squaring means of the feeding machine has its edge inserted between the gripper g10 and the part t10; the cam bars are so shaped that as the sheet proceeds forward, the attachment means take up the relative positions shown in Fig. 37 as the right-hand end of the sheets are released from the supporting bars (d3 Fig. 4) whereupon the sheet K is now gripped between the serrated surfaces and the attachment means move into the position shown in Fig. 12. As the gripping devices (illustrated in Fig. 12), carried by the main conveyor pass down over the end of the sprocket wheel c7 rotating about its horizontal axis; these attachment means intermesh with the attachment means just described on the transfer conveyor, and the cam bars (such as c3 and c4 Figs. 18 and 19) bring the parts G³ and F³ (Fig. 12) into relative positions such that the gripping parts as they pass over the upper edge of the sheets are brought into position in relation thereto as shown in Fig. 12, the cams causing the grippers to close and firmly grip the upper edges of the sheets which are thus attached to the main conveyor; as the gripping devices on the main conveyor grip the sheets, the gripping devices on the transfer conveyor are moved by their respective cam bars into the position shown in Fig. 38, and on comparing this figure with Fig. 37 it will be seen that the gripping devices g10 and t10 are raised clear of the top edges of the sheets, and are thus permitted to pass freely round the sprocket wheel t12 (see Figs. 24 and 25) of the transfer conveyor, the sheets being carried forward by the main conveyor into and through the furnace and cooling chamber.

Figs. 36, 37 and 38 show the parts in the relative positions they occupy at the points 150

XXXVI, XXXVII, and XXXVIII of Fig. 25. The transfer arrangement just described may be modified to suit the case in which the sprocket wheels of the transfer conveyor may be vertically disposed as in Figs. 1 to 6, in which case the axes of the sprocket wheels of the transfer conveyor are preferably obliquely disposed as in Figs. 26, 27 and 39 to 43. In Figs. 26 and 27 c3 is the rearmost sprocket wheel of the main conveyor, and C³ and T³ are the main and transfer conveyors and t8 and t9 the sprocket wheels of the transfer conveyor.

The gripping devices t11 and g11 are similar to those just described and are respectively pivoted by pins 52 to a lever 53 which in turn is pivoted by pins 54 to spaced brackets 55 carried from the links of the transfer conveyor T³ guided by the rollers 56 in the obliquely disposed guide 57. The part t11 is connected by a spring 58 and pins 70 to the lever 53, the spring tending to hold these two parts in the relative positions shown in Fig. 40. Cam bars 59 and 60 are provided to control the movement of the lever 53, and cam bar 61 is fitted to control the movement 25 of the gripper g11 and gripping part t11.

As the transfer conveyor passes along the left-hand edge of the table of the feeding machine the attachment devices are, by the combined operation of the cam bars and springs, turned into the position shown in Fig. 40, the edge of the sheet K is fed forward by the squaring pins and is inserted between the open gripping edges of t11 and g11; the cam bar 61 then permits the gripping surfaces to close as shown in Fig. 41. As the sheets fall into the vertical position, when 30 free from the feeding machine, and the bar d3 (Fig. 4) the weight of the sheets causes the gripping device to take up the position shown in Fig. 42 the spring 58 being overcome by the downward force due to the weight.

Gripping devices as shown in Fig. 12 are fitted to the main conveyor, and as they respectively turn inwardly when following the contour of the main sprocket wheel c8 they mesh with the attachment means just described on the transfer conveyor, suitable cams such as f9 (Fig. 12) are provided, and the slot f6 and pin f1 are so arranged that the gripping parts F³ and G³ are then raised higher than the top edge of the sheets, when the gripping surfaces are in line with the sheet they are lowered when cam bars such as g11 (Fig. 12) then operate the grippers G³ and cause them to grip the upper edges of the sheet and so attach the latter to the main conveyor, after which the gripping devices on the transfer conveyor are opened by the cam bars 61 (see Fig. 43) and move upwardly clear of the sheets which are then conveyed through the furnace.

Figs. 40, 41, 42 and 43 show the parts in the relative positions they occupy at the points XL, XLI, XLII and XLIII of Fig. 26.

The use of a transfer conveyor between the feeding table and the main conveyor may in some cases be dispensed with, the sheets being transferred directly from the feeding machine to pivoting grippers on the main conveyor which is extended to pass alongside the left-hand edge of the feeding machine. Figs. 32 and 33 show the general arrangement of this modification and Figs. 44 to 46 show suitable pivoting gripping devices.

In Figs. 32 and 33, c33 is the sprocket wheel of the main conveyor having its axis vertical, D the feeding machine and K the sheets. Figs. 44

to 46 show the details of the gripping devices for this modification, the part t13 is pivotally attached by the pins 62 in the slot 63 of the carrier bars such as B (Fig. 34) of the main conveyor, the cams 64 to control the movement of t13, and 65 and 66 to control the movement of the gripper g13 are provided; as the gripping devices pass the left-hand edge of the table of the feeding machine D, the cams move the gripping devices into the relative positions shown in Fig. 44, and the sheets K fed forward by the feed belt enter between the open gripping surfaces, the sheets are then gripped as shown in Fig. 45 and, when the sheets are released from the feed belts, they and their attachment means turn into the position shown in Fig. 46 in which the sheets, vertically disposed, are gripped by the conveyor attachment means and are carried by the latter through the furnace.

Figs. 44, 45 and 46 show the parts in the positions they occupy at the points XLIV, XLV, XLVI of Fig. 33.

Simplified take-off means may with this arrangement conveniently be provided comprising cams which open the gripping surfaces whereupon the sheets may be taken off by hand and stored in horizontal piles.

Where the sheets have turned-over or beaded edges the transfer conveyor may be replaced by a suitable bar arranged between the feeding machine and the main conveyor. Such arrangement is illustrated in Figs. 28 to 31, in this case the axis of the main sprocket wheel c14 is vertical, and the main conveyor C may be fitted with carrier bars, hooked attachment means and 110 grippers as shown in Figs. 8 to 10; the feeding machine has combined with it a beading machine and as the sheets are fed from the beading machine by the squaring pins the turned-over edges k1 (see Fig. 29) of the sheets K pass over 115 the bevelled top edge of the bar Z raising the latches t14.

When the sheet is released by the bar d3 (see Fig. 4) the sheets turn about their beaded edges which are supported by the bar Z (see Fig. 30) 120 into the vertical position and are propelled along the bar Z, the top bevelled edge of which has a forward downward slope so that their beaded edges pass over the hooked portions f3 (see Fig. 9) on the main conveyor carrier bars B, and are 125 held in position by the grippers G which are operated by suitable cam bars such as c3, c4.

Figs. 29 and 30 show the relative positions of the parts at point XXIX of Fig. 28, the parts taking the position shown in Fig. 31 at the point 130 XXXI of Fig. 28.

Having now fully described my invention I declare that what I claim and desire to secure by Letters Patent is:—

1. In a furnace for treating metal sheets, in 135 combination:—a furnace; an endless conveyor one part of which traverses the upper portion of the furnace longitudinally; members adapted to carry the sheet attachment means and each connected to the conveyor by means which permit 140 substantial vertical movement between the member and the conveyor; sheet attachment means comprising a sheet engaging part fixed to the said member, and a gripper carried by the said member and movable relatively to the said sheet engaging part; and longitudinal cam bars adapted 145 to operate the grippers.

2. In a furnace for treating metal sheets, in combination:—a furnace, an endless conveyor one part of which traverses the upper portion of 150

the furnace longitudinally; members adapted to carry the sheet attachment means and each connected to the conveyor by means which permit substantial vertical movement between the member and the conveyor; sheet attachment means comprising a sheet engaging part fixed to the said member and of hook-like configuration with which the folded top edge of the sheet is adapted to engage, and a gripper carried by the said member and movable relatively to the said hook-like sheet engaging part; and longitudinal cam bars adapted to operate the grippers.

3. In a furnace for treating metal sheets, in combination:—a furnace; an endless conveyor one part of which traverses the upper portion of the furnace longitudinally, members adapted to carry the sheet attachment means and each connected to the conveyor by means which permit substantial vertical movement between the said members and the conveyor; sheet attachment means comprising a sheet engaging part fixed to the said member, a gripper pivoted to the said member by a longitudinally disposed pivot, said engaging part and gripper being adapted to grip the plain edge of a sheet; and longitudinally disposed cams adapted to operate the gripper.

4. Apparatus as claimed in claim 1 in which the member carrying the sheet attachment member is connected to the conveyor by means which permit angular as well as vertical movement of the member relatively to the conveyor.

5. In combination with apparatus claimed in claim 1 lugs on the sheet attachment means, and longitudinal cams adapted as the said means approach the furnace mouth to hold the attachment means in their lowermost position in relation to the conveyor, and to hold the gripper open, and as the sheets enter the furnace to close the grippers and leave the attachment means free to move vertically relatively to the conveyor.

6. In a furnace for treating metal sheets, in combination; a furnace, an endless conveyor one portion of which moves longitudinally in line with the upper part of the furnace; sheet attachment means connected to the conveyor and adapted to connect the upper edges of the sheets to the conveyor so that the sheets are suspended vertically in line and conveyed longitudinally of the furnace; loading means by which an attendant is enabled to bring into engagement with said attachment means the attachment edges of successive sheets, too large and flabby to be lifted by hand into such engagement, said loading means comprising a table, the top of which is level with the sheet attachment means, aligning means formed by fixed stops located in a vertical plane coinciding with said attachment means and adapted to engage a longitudinal edge of a sheet slid transversely across the table and to align it in the said plane.

7. In a furnace for treating metal sheets, in combination; a furnace, an endless conveyor one portion of which moves longitudinally in line with the upper part of the furnace; sheet attachment means connected to the conveyor and adapted to connect the upper edges of the sheets to the conveyor so that the sheets are suspended vertically in line and conveyed longitudinally of the furnace; loading means by which an attendant is enabled to bring into engagement with said attachment means the attachment edges of successive sheets, too large and flabby to be lifted by hand into such engagement, said loading means comprising a table, the top of which is

level with the sheet attachment means, aligning means formed by fixed stops located in a vertical plane coinciding with said attachment means and adapted to engage a longitudinal edge of a sheet slid transversely across the table and to align it in the said plane, means guided to move parallel with the conveyor and adapted when actuated to engage a transverse side of the sheet and whilst maintaining said edge in said alignment to propel it longitudinally until the said longitudinal edge of the sheet is in engagement with the sheet attachment means, and until the sheet is clear of the table.

8. In a furnace for treating metal sheets, in combination:—a furnace; an endless conveyor having a part moving longitudinally of the furnace; sheet attachment means carried by the conveyor and each comprising a hook-shaped member adapted to engage the turned-over upper edge of the sheets and support the sheets from the conveyor so that they hang vertically in line; loading means by which an attendant is enabled to bring into operative engagement with the said attachment means the attachment edges of successive sheets, too large and flabby to permit them to be lifted by hand with said engagement, said loading means comprising a table the top of which is level with the sheet attachment means, aligning means formed by fixed stops located in a vertical plane coinciding with said attachment means, and adapted to engage the attachment edge of a sheet slid transversely across the table and to align said edge in the said plane, means guided to move parallel with the conveyor and adapted when actuated to engage a transverse side of the sheet and whilst retaining the sheet in said alignment to propel it longitudinally until the said folded-over edge of the sheet is in engagement with the hook-shaped parts of the sheet attachment means.

9. In a furnace for treating metal sheets, in combination;—a furnace, an endless conveyor one part of which is moved longitudinally of the upper part of the furnace; members adapted to carry the sheet attachment means and each connected to the conveyor by means which permit substantial vertical movement between the conveyor and the member; sheet attachment means comprising a sheet engaging part of hook-like shape fixed to the said member; a gripper carried by the member and movable relatively to the said hook shaped part; longitudinal cam bars to operate the grippers; and loading means by which an attendant is enabled to bring the folded-over edges of successive sheets into engaging relationship with said attachment means, said loading means comprising a table on to which may be slid the successive uppermost sheets of a pile of sheets, aligning means formed by fixed stops located in a vertical plane coinciding with the sheet engaging means, and adapted by engagement with the folded-over edge of a sheet slid transversely to locate the said edge in said plane, the height of the table being such that the said edge is slightly above the said hook-like parts, means guided to move in a direction parallel to the conveyor and adapted when actuated to engage a transverse side of the sheet and whilst maintaining said edge in said alignment to propel it longitudinally over the table until the folded-over edge of the sheet is in engaging relationship with the hook-like parts, a longitudinal forward extension of the table adapted to support the under side of the end of the sheet remote from the attachment means, and so disposed laterally

- that when the sheet is moved clear of the table the weight of the sheet pulls the said end over the said extension whereupon the sheet falls gradually into the vertical about the said hook-like parts as a pivot, the said longitudinal cam bars being so arranged that they then cause the grippers to engage the folded-over edges of the sheet and retain them in position on the hook-like parts.
10. In combination with the elements of claim 7, a sheet edge bending machine so located in relation to the table and the conveyor that when a sheet is aligned on the latter its attachment edge is in operative relationship with the said machine whereby upon operation of the latter the said edge is bent over in alignment with the line of hook-like supports carried by the conveyor with which the said edge has to engage as the sheet is fed forward.
11. In a furnace for treating metal sheets, in combination:—a furnace; a furnace conveyor having a part which moves longitudinally through the furnace; members adapted to carry the sheet attachment means and each pivotally connected to the conveyor by a longitudinally disposed pivot; sheet attachment means carried by the said member and comprising a part fixed to the said member, and a cam operated gripper connected to the said member by a longitudinal pivot, said fixed part and gripper forming fixed and movable jaws between which the plain top edge of the sheet is adapted to be gripped; longitudinal cam bars adapted to operate the gripper; and longitudinal cam bars adapted to operate the said member as the said part of the conveyor carrying the member approaches the furnace and to turn the said member about its longitudinal pivot through a right angle, and bring the gap between the fixed part and the open gripper into a horizontal position; loading means by which an attendant can load the sheets into the said horizontally disposed moving jaws, said loading means comprising a table the surface of which is at the same level as the gap between the said jaws when turned into a horizontal position, aligning means comprising fixed stops so located that when the attachment edge of a sheet on the table is caused to abut against them, the said edge is in engaging alignment with the said gaps, and means guided to move longitudinally which when actuated engage a transverse side of the sheet and propel it forwardly longitudinally until the said edge of the sheet is inserted in the said gap, the gripper operating cams actuating the grippers to engage the said edge after it has entered the gap, and the longitudinal cam operating the pivoted members carrying the attachment means, being so shaped that the said members as soon as the attached sheet has been moved clear of the table, are turned with the sheet into the vertical.
12. In a furnace for treating metal sheets, in combination:—a furnace; a main conveyor a part of which traverses the upper portion of the furnace longitudinally; sheet attachment means carried by the main conveyor; a transfer conveyor located outside the furnace and a part of which is in line with the said part of the main conveyor; and sheet attachment means carried by the transfer conveyor on to which the sheets are loaded and from which they are transferred to the main conveyor.
13. In a furnace for treating metal sheets, in combination:—a furnace; a main conveyor a part of which traverses the upper portion of the fur-
- nace longitudinally; sheet attachment means carried by the main conveyor; a transfer conveyor located outside the furnace and a part of which is in line with the said part of the main conveyor; sheet attachment means carried by the transfer conveyor on to which the sheets are loaded and from which they are transferred to the main conveyor; and loading means comprising a table the top of which is level with the sheet attachment means of the transfer conveyor, stops located in a vertical plane coinciding with said means and adapted to engage the longitudinal edge of a sheet slid transversely across the table and locate said edge in line with the said sheet attachment means of the transfer conveyor.
14. In a furnace for treating metal sheets in combination:—a furnace; a main conveyor traversing the upper portion of the furnace longitudinally and carried by sprocket wheels; sheet attachment means carried by the main conveyor; a transfer conveyor located outside the furnace and carried by sprocket wheels; sheet attachment means carried by the transfer conveyor, the axes of the sprocket wheels of the main conveyor and the axes of the sprocket wheels of the transfer conveyor being respectively disposed in planes which are approximately at right angles, and the said conveyors being so arranged that they overlap, the sheet attachment means of the main conveyor meshing at the overlap with the sheet attachment means of the transfer conveyor, so that the sheets loaded onto and carried by the transfer conveyor are transferred to the main conveyor.
15. The combination with the elements claimed in claim 14:—of means for driving the forward sprocket of the main conveyor; longitudinal movable bearings in which the rear main sprocket wheel of the main conveyor is mounted; yielding means tending to move the said bearings so as to maintain the forwardly moving part of the main conveyor taut; gearing between the rear sprocket wheel of the main conveyor and the forward sprocket wheel of the transfer conveyor which includes a spur pinion adapted to drive the latter sprocket wheel geared to a spur wheel on the shaft of the rear sprocket of the main conveyor, to which pinion secondary angular movement is imparted by the longitudinal movement of the said bearings to maintain the overlapping sheet-attachment means of the respective conveyors in synchronous meshing.
16. In a furnace for treating metal sheets, in combination:—a furnace; a main conveyor part of which passes through the furnace; a transfer conveyor located outside the furnace; sheet attachment means carried by the main and transfer conveyors comprising hook-like parts adapted to support the sheets by engaging their folded-over edges; and a series of pivoted latches carried by fixed transverse pivots, located over the forwardly moving side of the transfer conveyor, said latches normally hanging down and engaging the sides of the sheets when the latter turn into the vertical, and retaining the beaded portions in position on the hooks, said latches being turned out of the said vertical position by the sheets whilst the planes of the latter are maintained horizontal by the loading means.
17. In a furnace for treating metal sheets, in combination:—a furnace; a main conveyor part of which passes through the furnace; a transfer conveyor located outside the furnace; sheet attachment means carried by the main and transfer conveyors comprising hook-like parts adapted

to support the sheets by engaging their folded-over edges; means by which the end of the transfer conveyor adjacent the main conveyor is guided so as to slope downwardly, so that the hook shaped parts of the sheet attachment means of the transfer conveyor, after the folded-over edges of the sheets are engaged by the hook-shaped parts of the sheet attachment means of the main conveyor, are moved downwardly clear of the said folded-over edges.

18. In combination with apparatus as claimed in claim 11 a transfer conveyor having a part in line with the said part of the furnace conveyor; said transfer conveyor having sheet attachment means, carrying members, and operating cams therefor constructed and operating in the same manner as those of the said furnace conveyor; means for turning the sheet attachment means of the transfer conveyor so that fixed and movable jaws thereof are horizontally disposed so as to take the edges of horizontally disposed sheets; which latter means when the sheet edge is engaged by said attachment means permit the latter and the sheet to turn down into the vertical position; means which after the sheet attachment means of the two conveyors are meshed in line and the sheets engaged by the furnace conveyor sheet attachment means, are adapted to release the grippers of the transfer sheet attachment means, and to raise the latter clear of the edge of the sheet so as to permit their return movement across the line of the sheets.

19. In a furnace for treating metal sheets, in combination:—a furnace, a conveyor, a part of

35

40

45

50

55

60

65

70

75

which traverses the furnace longitudinally; sheet attachment means carried by the conveyor and comprising hook-like parts to engage the folded-over attachment edges of the sheets; a fixed transfer bar located in line with said hook-shaped parts and adapted to take the folded-over edges of successive sheets loaded on to the bar; loading means comprising a table and locating means by which the sheets are guided into position so that the folded-over edge of each sheet is brought on the inside of the bar; and latches with fixed pivots at right angles to the vertical plane containing the said bar and adapted when the sheets are released from the support of the table to engage the vertical parts of the sheets and hold them against the bar.

20. In a furnace for treating metal sheets, in combination:—a furnace; a conveyor having a part moving longitudinally of the furnace; sheet attachment means carried by the said conveyor; and loading means comprising a table, level with said sheet attachment means, and provided with longitudinally disposed slots; sheet locating means for locating the attachment edges of sheets on the table in line with the said sheet attachment means; levers in alignment for feeding the sheet forwardly and extending through the said slots and attached to a transversely disposed shaft fitted with an operating pedal, the depression of said pedal causing said levers to move along said slots and to feed said sheet forwardly.

EVELYN EDWIN GRIFFITHS.
